(57) **CLAIM**

The ornamental design for a telephone line seizure module, as shown and described.

DESCRIPTION

FIG. 1 is perspective view from above of the telephone line seizure module of my new design.

FIG. 2 is a top plan view of the module of my new design.

FIG. 3 is an elevational view of the rear of the module of my new design.

FIG. 4 is an elevational view of the front of the module of my new design.

FIG. 5 is an elevational view of the right side of the module shown in FIG. 1.

FIG. 6 is an elevational view of the left side of the module shown in FIG. 1; and,

FIG. 7 is a bottom plan view of the module of my new design. The broken line elements in FIGS. 1, and 2 are environmental, and are not a part of my new design.

1 Claim, 4 Drawing Sheets Fig. 2
